(57) CLAIM

The ornamental design for a hand shower, as shown and described.

DESCRIPTION

1.1 is a side view of a hand shower, showing my new design;

1.2 is a side view thereof;

1.3 is a front view thereof;

1.4 is a rear view thereof;

1.5 is a bottom view thereof; and

1.6 is a top view thereof.

The broken lines are shown for the purpose of illustrating portions of the hand shower that forms no part of the claimed design.
